UNITED STATES PATENT OFFICE.

THOMAS C. KOPETKEE, OF CROFTON, NEBRASKA.

CLOTHES-LINE.

1,165,517.

Specification of Letters Patent. Patented Dec. 28, 1915.

Application filed December 5, 1913. Serial No. 804,912.

To all whom it may concern:

Be it known that I, THOMAS C. KOPETKEE, a citizen of the United States, residing at Crofton, in the county of Knox and State of Nebraska, have invented certain new and useful Improvements in Clothes-Lines, of which the following is a specification.

This invention relates to clothes lines and the object of the invention is the provision 10 of a novel, inexpensive and efficient line which may have its separate sections disconnected one from the other and which is provided with means for interlocking the sections, the said means serving as a clutch 15 to hold the clothes in position upon the line.

A further object of the invention contemplates the provision of a clothes line wherein in the pins or clutches employed for the purpose of suspending articles therefrom, 20 are constructed in such a novel and peculiar manner as to form, when assembled, a portion of the line itself, the line sections, of which there may be any number, serving as a resilient means to maintain the pins or 25 clutches in engagement with the clothes acted upon.

The above and additional objects are accomplished by such means as are illustrated in their preferred embodiment in the accompanying drawings, described in the following specification and then more particularly pointed out in the claims which are appended hereto and form a part of this application.

35 In describing my invention in detail reference will be had to the accompanying drawings wherein like characters denote like or corresponding parts throughout the several views, and in which:—

40 Figure 1 is a side elevation illustrating the manner in which the several sections comprising my improved clothes line are connected; Fig. 2 is a top plan view of the line, the post and the pins being shown in 45 section; Fig. 3 is an enlarged side elevation of one of the pin sections or jaws; and Fig. 4 is a face view of one of the said pins or jaws.

Referring now to the drawings wherein 50 is illustrated the preferred embodiment of my invention the numeral 1 designates the supporting structure, which in the present instance comprises a pair of spaced apart posts, to which the line comprising my invention is secured. The clothes line is pref-

erably composed of wire and comprises a plurality of wire sections, the end section 2 herein illustrated having an eye 3 formed in one end thereof to provide a securing means therefor. The section 2 is bent as at 4 at a point intermediate its ends to provide a loop 5, the said loop being formed or shaped as illustrated to advantage in Fig. 2 of the drawings by bending a strand of wire of which the said section 2 is composed to extend to the said point 4 where it is fastened upon itself as shown.

The adjacent section, designated as an entirety by the numeral 6 is provided with a double loop formed by bending the wire of 70 which the said section is composed as at 7, the bent portion 8 thereof forming a single loop from which the other loop 9 comprising the double loop is formed, the free end of the double loop being secured as at 10 to 75 the wire stand 6 at the point 7 above mentioned. The opposite end of the section 6 is bent in substantially the same manner as the section 2 before noted, therefore the reference numerals applied to the said section 2 80 with the exception of the numeral 3 are applicable to the section 6.

The next or adjacent line section designated as an entirety by the numeral 11 is a duplicate of the section 6, therefore the 85 numerals applied to the said section 6 are applicable thereto. Should the section 11 form the end section, as illustrated herein, a small loop 12 is formed upon the opposite extremity from that upon which the double 90 loop is formed to provide a securing means therefor.

Duplicate clamping jaws of which there are two, designated 13 and 14 respectively are provided, the meeting faces of the said 95 jaws being toothed or serrated as at 15, the teeth of one jaw interlocking with the teeth of the other. By fitting the said jaws through the single loop of one line section and the double loop of the next or adjacent 100 line section as is illustrated in Fig. 1 of the drawings, it is apparent that the said two jaws are maintained in engagement one with the other, the tension of the line serving as a retaining element. As shown, the 105 upper portion of the respective jaws 13 are flared outwardly or away from one another to form handles by means of which they may be operated, the said jaws when forced toward each other adapted to disengage the 110

teeth 15 and to permit the fastening or suspension of clothes or other articles therefrom.

From the above, taken in connection with the accompanying drawings it is apparent that the clutches comprising the jaws 13 and 14 form an interlocking means for the several line sections; that the said jaws are normally maintained with one set of teeth 10 in mesh with the other, with the tension of one line section between the loop comprising to maintain the said jaws in such relation; and that by extending the single loop of one line section between the loop comprising 15 the double loop of the adjacent line section, a positive supporting element for the clutches is provided.

In reduction to practice, I have found that the form of my invention, illustrated in the drawings and referred to in the above description, as the preferred embodiment, is the most efficient and practical; yet realizing that the conditions concurrent with the adoption of my device will necessarily vary, 20 I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. A clothes line including a plurality of 35 clothes line sections, the respective sections extending in overlapping relation, clamping devices connecting the respective sections, the said devices being embraced by the respective overlapping terminals of the adjacent sections for the purpose specified.

2. A clothes line including a plurality of 40 clothes line sections, clamping devices connecting the respective sections, each clamping device comprising clamping jaws on one

side of the sections and divergent arms upon 45 the other side thereof.

3. A clothes line including a plurality of clothes line sections, the meeting terminals of the respective sections being disposed in overlapping relation, clothes clamps connecting the respective sections, the several clamps being embraced by the overlapping portion of the clothes line sections, each clamp comprising divergent clamping jaws 50 adapted to be held in yielding contact by 55 the mentioned sections.

4. A clothes line comprising a plurality of detachable line sections, each section being composed of a single strand of wire, a double loop formed upon one end of each 60 section, a single loop formed upon the opposite end of each section, and clothes clamps supported by the said sections, the said clamps being adapted to fit within the double loop of one line section and the single 65 loop of the adjacent line-section to serve as a securing means therefor.

5. A clothes line comprising a plurality of detachable line sections, each section being composed of a single strand of wire, a 70 double loop formed upon one end of the said wire strand, a single loop formed upon the opposite end of the said wire strand, securing means for the said line sections comprising a pair of curved clamping jaws, the 75 meeting faces of the said jaws being provided with teeth, the teeth of one jaw interlocking with the teeth of the other, both of the said jaws fitting within the double loop 80 of one section and the adjacent single loop of the meeting section to form a securing means for said section.

In testimony whereof I affix my signature in presence of two witnesses.

TOM C. KOPETKEE.
